UNITED STATES PATENT OFFICE.

LE GRAND TERRY, OF HORSEHEADS, NEW YORK.

DESIGN FOR A HANDLE.

SPECIFICATION forming part of Design No. 25,171, dated February 18, 1896.

Application filed May 22, 1895. Serial No. 550,271. Term of patent 14 years.

To all whom it may concern:

Be it known that I, LE GRAND TERRY, a citizen of the United States, residing at Horseheads, in the county of Chemung and State 5 of New York, have invented and produced a new and original Design for Handles, of which the following is a specification, reference being had to the accompanying drawings, showing a part thereof.

Figure 1 is a view in perspective of my design, and Fig. 2 is a sectional view of same.

A is the plate provided with a socket b, within which is movably located handle B, the ends of which are flat and parallel with 15 each other, while the sides thereof are also

parallel with each other, the width of said sides being at right angles to the width of the ends of said handle. The side of handle B constituting the grip is curved, the convexed face being the inside face when in its 20 normal position and the lower face when in its raised position.

What I claim is—

The design for a handle herein shown and described.

LE GRAND TERRY.
